UNITED STATES PATENT OFFICE.

SAMUEL M. WARD, JR., OF WOODMERE, NEW YORK, ASSIGNOR TO JOHN T. CLARKE, OF NEW YORK, N. Y.

ELECTRIC SIGNALING SYSTEM.

1,241,062.

Specification of Letters Patent. Patented Sept. 25, 1917.

Application filed December 24, 1907, Serial No. 407,936. Renewed December 15, 1916. Serial No. 137,265.

To all whom it may concern:

Be it known that I, SAMUEL M. WARD, Jr., a citizen of the United States, residing at Woodmere, county of Nassau, Long Island, 5 State of New York, have invented certain new and useful Improvements in Electric Signaling Systems, of which the following is a specification.

My invention relates to electric signaling systems, and more particularly to automatic electric railway signals of that type applied to a single track which constitutes a block between turn-outs.

This application is in the nature of a 15 continuation of my co-pending application Renewal Serial Number 137264, renewed December 15, 1916; original Serial Number 384955, filed July 22, 1907, for electric signaling systems.

20 One of the objects of my invention is to provide a durable and efficient signaling system of the above type.

Another object of the invention is to provide a signaling system which will permit cars to enter at opposite ends of the block simultaneously, or to enter at one end and leave at the other end simultaneously without disarranging the signaling system or disturbing set signals, and which will permit a car which has improperly entered the signal block to back out of the same without disturbing the signals.

It frequently happens that a car is run into a block when it has no right there, and 35 should be immediately backed off. Such cases may arise where a car has a danger signal thrown directly in front of it as the car is about to enter the block, or where entering simultaneously with the car at the 40 other end, said last car backs off and reenters to set a danger signal against the first car; in either of which cases the car against which the danger signal is set should back off without affecting said signals, and object 45 of this invention is to provide means situated within the block for allowing the car so situated to back out of the block without affecting the signals, and this without having to disturb its collector.

50 Another object of the invention is to provide a quick release for the locking mechanism of the controller actuating pawls as well as for the pawls themselves, so that the liability of the pawls interfering with each 55 other by having the magnet of each ener-

gized at the same time will be reduced to a minimum; and to provide means for operating said pawls in a predetermined order should the operating magnets be simultaneously energized by cars entering and leaving 60 the block simultaneously; thus providing a controller which cannot be disarranged by any possible order in which cars may enter or leave the block, due to ignoring signals or otherwise.

65 Another object of the invention is to supplement the dash pots used with the trolley switches, which are expensive and require considerable care, by a simple, inexpensive and reliable apparatus for governing the 70 controller circuits.

Still another object is to remove the signal lamps from the main signal circuit, and to so arrange the system that both signals at each end of the block are placed in a local circuit which, if desired, may be supplied with a separate source of energy, and which are controlled by line relays.

75 My invention will be best understood by the following description, reference being 80 had to the accompanying drawings, in which—

Figure 1 is a diagrammatic view of my signaling system as applied to a section of single track electric road which connects the 85 double tracks or turn-outs at each end.

Fig. 2 is a side elevation of the signal casting showing the signals and the controller with its actuating magnets; and

Fig. 3 is a modification of one of the 90 circuits of Fig. 1.

Referring to Fig. 1, 1 is an incandescent lamp in a local circuit which remains closed all the time. 2 is a target or red transparency which is normally held aloft by solenoid 3, but which is allowed to drop over the lamp 2 when the solenoid is deenergized. The solenoid is placed in a local circuit 4 which is held normally closed by a relay 6 of relatively high resistance. The target 100 carries a contact to bridge contacts 11 for short circuiting resistance 9, when the target is released to cover lamp 1.

A is a step by step controller comprising a ratchet wheel 12 which carries a finger 15 105 for engaging switch 17 and a pin 16 for engaging a projection on the frame (not shown) to limit the movement of the wheel. The switch 17, having three arms for controlling circuits hereinafter to be mentioned, 110

is mounted on a shaft and held in either of its operating positions by a spring 18. A pawl 20 for advancing the controller is operated by magnet 19, which is energized 5 through circuit 21 and controlled by relay 6, and the trolley switch 66. A magnet 28 which is energized through circuit 29 operates pawl 30 to restore the controller; the circuit 29 being controlled at contacts 31 and 33.

38 is an incandescent lamp (in this case green) situated in a local circuit 10 which is controlled by relay 80 of relatively low resistance, and switch 24. This lamp constitutes the "caution" signal or return indication and may be replaced by a target and lamp similar to the one above mentioned for circuit 4 in which case at least one white light will always be displayed to direct the 10 motorman's attention in the direction of the signal stand. Situated at the entrance of the block is a device for controlling the magnets 19 and 28, which consists of a switch 66 for closing contacts 22, and a magnet 83 for controlling contacts 33. An elongated contact 82 is carried beneath a suitable frame secured to the trolley wire so as to be engaged by the trolley wheel or shoe to energize the magnet 83; and the switch 66 is 15 mounted on the frame in operative relation to a tongue 65 which is suspended in the path of the trolley wheel and so pivoted that it will operate to close switch 66 only when engaged by a car which is entering the block. The contact 82 is connected to the trolley wire by a conductor 86 which includes the magnet 83 for controlling contacts 33. The magnet is preferably carried on a frame with switch 66. The mechanism at the other end 20 of the block is a duplicate of that already described and needs no further mention here. By this arrangement, the clearing of the signals is under the control of the motorman and the signals are only cleared when the car engages the contacts with the controller on. The cars in regularly entering the block 25 will always coast past the contacts.

A conductor 34 extends along the block for setting the signals and has similar trolley and ground connections at each end. The trolley branch at A includes contacts 35, relay 6, and resistance 9; the ground branch including contacts 37 and relay 80; while the branch at B includes similar apparatus. 30 A second conductor 32 extends along the block having similar trolley and ground connections at each end. The trolley connection at A includes contacts 33 and wire 86; the ground branch including contacts 31, 35 wire 29 and magnet 28.

The high resistance relays 6 and 6' are designed so that either of them will attract its core when energized with one of the resistances 9 or 9' in circuit, and yet will be 40 capable of remaining in circuit for any

length of time with the resistance cut out, without undue heating. To accomplish this it is only necessary to use a slightly larger wire than usual in winding the relay coil.

The relatively low resistance relays 80 and 80' are so designed that neither of them will attract its core to close contacts 85 or 85' when it is energized with one of the resistances 9 or 9' in circuit; but upon the resistance being bridged the relay will become 45 energized sufficiently to attract its core and close contacts 85 or 85'. The resistances 9 and 9' are such that when cut in and out of the circuit they will vary the current in line 34 by a considerable percentage of its normal value, thus insuring the proper operation of the relays at all times.

Fig. 1 shows the condition of the system after a car has entered the block at the left, and its operation is as follows:

A car entering the block at A will engage tongue 65 to close contacts 22, completing a circuit from the trolley wire through contacts 23 and magnet 19 to ground. Magnet 19 being energized will operate pawl 20 to 50 turn disk 12 one step in an anti-clockwise direction causing finger 15 to engage the right hand edge of switch 17 and throw the same to close contacts 31 and 37 and open contacts 35.

A detent, not shown, holds the disk in its operated position and spring 18 holds switch 17 in its operated position. The closing of contacts 37 completes a circuit from ground at A through relay 80, wire 36, contacts 37, conductor 34, contacts 35' at B, wire 8', relay 6', resistance 9' to trolley wire. The closing of this circuit energizes relay 6' causing it to attract its core and open circuits 4' and 21'. The opening of circuit 4' deenergizes sole- 105 noid 3' causing the red disk 2' to fall over (the normally burning) lamp 1' to indicate danger. Upon the signal being set, resistance 9' is bridged by a contact carried by the disk and the current in conductor 34 110 is increased to energize relay 80 sufficiently to cause it to close contacts 85. If contacts 25 have been previously closed by the de-energization of magnet 19, the closing of contacts 85 will light the green lamp to indicate a clear block ahead, but if the contacts 25 have not been closed, the lamp will be lighted upon the closing of these contacts, as the pawl returns to its normal position.

The closing of contacts 31 completes a 120 circuit from ground at A through solenoid 28, wire 29, contacts 31, and conductor 32, to contacts 33' at B, and another circuit which branches at contacts 31 at A, and leads to contacts 33 at A. From this it will be seen that a car in the block may energize solenoid 28 to return controller disk 12 and operate switch 17 to clear the signals when it leaves the block at either end, at which time it will close contacts 33 or 33' to ener- 125 130

size said magnet by completing a circuit from trolley wire through relay 83 (or 83' as the case may be), conductor 82, trolley wheel and car connections to ground. The 5 contacts 31' being normally open, prevent the operation of the controller at B when the car passes out of the block.

The opening of contacts 35 at A when the car entered prevents any possible setting of 10 the danger signal at that end by a car accidentally running into the block at B, since the circuit to relay 6 was immediately opened when the first car entered the block. Likewise, the relay 6' at B having opened 15 circuits 4' and 21' when energized, prevents any possible setting of the safety signal at that end, since its circuit is not only broken by the contacts at relay 6', but the circuit of solenoid 19' and relay 80' are also held 20 open.

It will thus be seen that a car over-runs 25 a danger signal and entering at the other end of the block can neither give nor receive another signal while the other car remains 30 in the block, nor can it clear the signals previously set by a car in the block, a defect common in signaling systems of this type now in use. It is necessary for a car in such a position to leave the block without 35 affecting the signals, and heretofore it has been impossible to accomplish this with any known signaling system without lowering the trolley collector in backing out past the trolley switch. With my system it is only 40 necessary for the motorman to start his car back and then open his motor circuit by turning his controller handle to the "off" position until he passes the trolley switch.

Should cars approach each end of the 45 block at the same time, the first one engaging its trolley switch will cause the circuit of the controller at the other end to be opened by relay 6 or 6', thus preventing the other car from setting any signals, even though it over-runs the danger signal just set ahead of it.

Should the cars engage their switches precisely at the same instant, each of the magnets 50 19 and 19' would be energized to throw switches 17 and 17' to open contacts 35 and 35', and close contacts 31—31' and 37—37'; the effect of which would be to connect conductor 34 to ground at each end of the block through relays 80 and 80'. The conductor 55 being so connected, no current can flow, hence neither car can receive a clear signal. The first motorman to appreciate this situation, due to not receiving a clear signal, and who backs his car off, will energize the 60 relay 83 at that end to close contacts 33 (or 33', as the case may be). The closing of these contacts will energize both solenoids 28 and 28' since both contacts 31 and 31' are closed, and both controllers will be operated 65 to restore the circuits to normal condition.

The car thus backing off will immediately re-enter and throw a danger signal against the car at the other end in the manner previously described. The other car thus having a danger signal set against it will back 70 out of the block, coasting past the trolley contacts at that end without affecting the signals, as previously described.

It makes no difference whether the cars back off at the same time or whether the one 75 slowest to back out comes out before the danger signal is set against it, for in either case it would back out with its controller at the on position (since a danger signal has not yet been set against it) to close contacts 80 33, in a manner previously described, but this will not affect the signals since, as in the first case put, if the cars are engaging the conductors 82 and 82' at the same time the controller will act just as if in response 85 to one car; and should the last car back out just before the other re-enters, as in the second case put; the contacts 31 and 31' will be open and the closing of contacts 33 will have no effect. Should the second car engage 90 its trolley contacts in backing out at the instant the first car engages its trolley switch on re-entering, the controller will have its magnets 19 and 28 simultaneously 95 energized, a contingency which can rarely happen with my type of controller, herein-after to be explained, and which adequately takes care of such a contingency when it does arise, by permitting the controller to respond to each car; with the result that 100 no signals are given, and the first car will be obliged to back out (with its controller on) without affecting the signals, since contacts 31 and 31' are now open and the first car to re-enter will set the signals in the 105 usual manner.

It may happen that cars enter the block simultaneously, and it frequently happens that a car accidentally over-runs a danger signal; in each case throwing the signals 110 out of order. In all other systems in which the trolley switch for energizing the magnets of the step by step controller is placed within the block, when a car over-runs a danger signal accidentally or otherwise, it 115 cannot back out of the block past said switch, leaving the signals undisturbed, without lowering its collector from the path of the switch, or having the conductor get out and throw some auxiliary hand switch, 120 which must be kept in a locked box to prevent it being operated by others.

The use of a trolley switch device situated within the block at each end for so governing the signal controller that a car 125 may back out of the block in which it has no right, without affecting the controller and without having to lower its collector, is an important feature. Whenever the block is used by cars having different destinations at 130

either end of the block, it is impossible to use a trolley switch device in each of the turn-outs at that end of the block since one car leaving the block by one turn-out at that end would advance the controller or not affect it at all, according to the type of switch used in the turnout, and another car leaving by the other branch at that end would operate to restore the controller, whereas the controller should have been restored in response to both cars leaving the block at that end since it was advanced by each of the cars when they entered at the other end.

Fig. 2 is a side elevation of the signaling casing containing the signals and the signal controller, with switch 24 removed from the core of solenoid 19 for the sake of clearness. The controller disk 12 carrying a finger 15 for operating switch 17, is mounted on a shaft journaled in supports not shown. The disk is operated by pawls 20 and 30 which are controlled and actuated by solenoids 19 and 28, the cores of which carry pivoted latches 57 which normally engage a knife edge or stud 51 at the foot of each pawl, as shown at the right. Each latch has a depending, and preferably a laterally projecting stud 53, which rides on the inclined upper flanged surface of cam block 52. The cam blocks which are substantially L shape in cross-section are stamped up from steel or brass sheet metal, and secured to a base plate through their lower flanges by screws or bolts.

Two standards or straps 49 slidingly support a rod 48 which is normally thrust to the right by spring 58 carried between one of the straps and an abutment 60 carried on the rod. The rod carries a hook 56 formed at its front end which is adapted to engage a depending arm 50, of cylindrical or other cross-section carried by pawl 30. The rod is drawn back by solenoid 19 against the action of spring 58 (as shown in Fig. 2), which normally holds the rod thrust forward in such a position that it will not interfere with the operation of pawl 30. The front surface of the hook 56 is of such curvature that arm 50 may slide on said surface when pawl 30 is operated, but never getting above it.

The left had latch 57 carries an upwardly extending arm which is bent laterally at its upper end as shown at 59, for engaging abutment 60 on the rod. In cross-section the lateral arm 59 resembles a half ellipse, the rear surface being substantially vertical while the lower surface is inclined. The abutment 60 presents a substantially vertical front while at its rear it is beveled off and rounded, as shown.

Solenoid 19 controlling the latch which carries arm 59 is designed to be more powerful than solenoid 28 and is controlled through contacts 22, while the relatively weak solenoid 28 is controlled through

contacts 33. The red transparency 2 is carried on a rock shaft supported below the shelf upon which the normally burning lamp 1 and the solenoid 3 for operating the transparency 2 are mounted; the green lamp 70 38 being mounted just below.

The operation of the controller is as follows:

A car entering the block will engage tongue 65 to momentarily energize solenoid 75 19, which in attracting its core engages pawl 20 through the latch and knife edge and at the same time causes the rear surface of arm 59 to engage the front surface of abutment 60, to force rod 48 back against 80 spring 58. As the core is drawn in, the disk 12 is advanced to throw switch 17 by engagement with finger 15, and the stud 53 riding up on the inclined surface of block 52, together with the pivotal action of the pawl, 85 causes the latch to simultaneously release pawl 20 and the rod 48 on the completion of its stroke, due to the knife edge slipping under the latch and the arm 59 being raised above abutment 60 so that the pawl and rod 90 will return to normal position by the respective springs 55 and 58 immediately on the completion of the controller movement. The closing of switch 17, which is held in either of its positions by spring 18, causes the signal to be set as heretofore mentioned. Each succeeding car now entering the block will operate the controller as above mentioned to advance finger 15 one step and the circuit of the green lamp at the entering end will be 100 momentarily opened by switch 24 (Fig. 1) carried on the core of solenoid 19, to indicate the operation of the controller, but switch 17 will remain undisturbed.

As a car passes out of the block (with its controller "on," one notch being sufficient) it closes contacts 33 to energize solenoid 28 for returning the disk one step backward, the last car leaving the block causing finger 15 to engage switch 17 and clear the signals. 110

From the above, it will be seen that each pawl is given a quick release on completion of its stroke and prior to the deenergization of its actuating solenoid by the trolley switch, a feature which is disclosed in my 115 above mentioned application, and which greatly diminishes the possibility of pawls 20 and 30 engaging the controller disk together when cars leave and enter the block about the same time, since the complete cycle 120 of the pawl movement is instantaneous.

In the particular system shown the period of energization of one of the controller solenoids is determined by the speed of the car bridging the extended contact 82, while 125 the period of energization of the opposite solenoid is only momentary. The contact 82 is made long enough to insure the proper operation of the controller by each solenoid, and the quicker the restrained pawl, which 130

is controlled by these contacts, can be released, the shorter may the contacts be with the same efficiency.

It would be undesirable to accomplish this result by shortening the period of time during which the locking solenoid was energized, by making only an instantaneous make and break at contacts 82, for the switch may fail to energize the solenoid. By providing the quick release of the rod 48 while the solenoid 19 is energized, the pawl 30 is only instantaneously restrained, insuring ample time for its operation and at the same time a good "wiping" contact may be used for closing the circuit of solenoid 19.

The operation of the controller when a car enters the block at the same instant that one leaves is as follows:

The car entering at A will engage tongue 65, closing contacts 22 to energize solenoid 19 and the car leaving the block at B will engage contact 82', closing contacts 33' to energize solenoid 28 at A. Solenoid 19 being stronger than solenoid 28 will over-power it and advance disk 12 one step by operating pawl 20, at the same time holding pawl 30 down in its normal position by the strong spring 55 connecting the pawls and by the engagement of the front surface of hook 56 with the arm 50 which is always in the path of the hook. Immediately that the latch of solenoid 19 reaches its inner position, the pawl 30 and rod 48 are released as heretofore explained, and pawl 30 is immediately operated by solenoid 28, which is held energized as long as contacts 82 are bridged by the trolley collector, which will be for an appreciable time after the pawl 30 has been released, since the time during which the pawl was restrained is instantaneous. When solenoid 19 is deenergized the latch is returned by spring 54 and its rounded front edge will slide up over the sloping back of the knife edge 51, dropping in position in front of it; while the inclined under surface of the arm 59 carried by the latch will engage the beveled back edge of abutment 60, (now in its forward position in front of the arm), and drop in position in front of the abutment so that the vertical faces will be engaged when solenoid 19 is again energized. As a matter of detail I prefer to give one or both of the engaging surfaces of arm 59 and abutment 60 a slight incline from right to left to avoid any tendency on the part of the arm to ride up above the abutment when it engages the same. The weight of the latch which may have a thickened head, or a weight attached, will be sufficient even with straight engaging surfaces, but if desired a spring (not shown) may be carried by the core at the latch pivot for holding the latch pressed in engagement with the inclined surface of the cam block. Suitably fixed guides for the latch extend-

ing up from the rear of the cam block may also be provided if desired, but the same are not deemed necessary.

It is obvious to those skilled in the art that many changes may be made in my system without departing from the spirit of my invention. For instance, the ground connection, including the resistance and one of the contacts, may be omitted, in which case when the trolley engages the contact connected to the magnet and the controller is in the off position no current will flow and the magnet will remain deenergized, but otherwise the operation will be the same as in the apparatus before described; also the quick release of the pawls may be accomplished by each pawl carrying a contact to open its own actuating circuit when it is operated, as set forth in my prior application above mentioned; or the green signal lamps may be replaced by a target and lamp, or both signals by a target only, or a semaphore.

All such modifications of the apparatus I aim to cover by the appended claims.

By the term setting a signal I wish to be understood as meaning the giving or displaying of a visual signal of any kind whatsoever, and by the term "clearing" the signal I mean the discontinuance of the signal, such as the extinguishing or shielding from view of a light, the shifting of a target from in front of the light, or a different position assumed by the semaphore or target as the case may be.

It will be seen from the above description that I have provided a system of the type described in which the controller and signals will be properly operated regardless of the time at or order in which cars enter and leave the block.

Having thus described my invention, what I claim and desire to secure by Letters Patent of the United States, is—

1. In a block signaling system, a signal line wire extending along the block, switches at each end of the block normally connecting the line wire to the same side of a source of power, a signal at the remote end of the block, signal-setting means at said end operatively related to the line wire and controlled through said line wire from the near end of the block for setting the signal, and a signal at the near end of the block operatively related to said line wire and controlled through said line wire to be set in response to said signal-setting means at the remote end of the block.

2. In a block signaling system, a signal at one end of the block, means for setting said signal, a signal circuit extending along the block for controlling said setting means, a signal at the opposite end of the block set through said circuit, and means for operating said last signal on the entrance of each

car of a possible series into the block while a preceding car occupies the block.

3. In a block signaling system, the combination of a signal, means for operating the signal, signal controllers one at each end of the block, means for operating the controllers, a signal circuit extending along the block, and electromagnetically-operated means at one end of the block operated 10 through said circuit in response to the operation of one of said controllers for governing the setting of the signal and preventing the operation of the other controller while the signal is set.

15 4. In a block signaling system, a signal circuit extending along the block, signal setting means at one end controlled through said circuit by the first car of a possible series entering the block for setting the signal 20 at that end, a signal at the other end controlled through said circuit by the setting of the first signal, and a switch operated in advancing the controller and controlled by the entry of each succeeding car of the series 25 for causing an indication of the controller movement to be given each of said cars without affecting said first signal.

30 5. In a signaling system, the combination with a step by step controller, of electromagnetically-controlled means for advancing and restoring the controller in response to each car of a possible series entering and leaving the block respectively, a signal set in response to the first movement of the controller, electromagnetic means for operating the signal, and means for assuring the operation of the controller by each car when cars enter and leave the block simultaneously.

35 6. In a signaling system, a signal at each end of a block, a block circuit the energization and deenergization of which controls the setting and clearing of said signals, a controller at each end of the block for energizing and deenergizing said circuit, electromagnetically-controlled means for advancing and restoring the controllers, circuits for energizing the same, and means whereby one of said last circuits is energized for a longer period than the other when cars enter and leave the block simultaneously.

40 7. In a block signaling system, the combination of a step by step controller at each end of the block, one of which is operated a step forward and backward respectively in 45 response to each car entering and leaving the block in a given direction, a danger signal set in response to the first forward movement of said controller and cleared by its last return movement, a signal set at the entering end of the block in response to the setting of said danger signal, danger and caution signals similarly arranged with respect to the other controller and governed thereby in response to cars entering and 55 leaving the block in the opposite direction,

two line wires only extending along the block for controlling and operating said signals, and means including a switch for causing an indication of the movement of the operating controller to be given each 70 following car entering the block after the signals are set.

8. In a signaling system, the combination of step by step controllers, one at each end of a block, one of said controllers operated 75 a step forward and backward respectively in response to cars entering and leaving the block in one direction, a danger signal set when said controller assumes its first forward movement and cleared when the controller is restored, the other step by step controller similarly operated in response to cars entering or leaving the block in the other direction, a danger signal similarly set by said controller, a single line wire for controlling the setting of either of said signals, and a signal set in response to the setting of one of said danger signals for indicating to the first car of a series the setting 80 of its danger signal.

9. In a block signaling system, the combination of a step by step controller at each end of the block, one of which is operated a step forward and backward respectively in 90 response to each car entering and leaving the block in a given direction, a danger signal at one end of the block set in response to the first forward movement of said controller and cleared in response to its last backward movement, a signal at the entering end set in response to the setting of the danger signal, means for causing an indication to be given each subsequent car to show the forward movement of its signal controller, signals and circuits similarly arranged and controlled by the other step by step controller in response to cars entering and leaving the block in the opposite direction, and a common line wire through which 95 the setting of the danger signals is controlled.

10. In a block signaling system, the combination of a signal, a step by step signal controller therefor, electromagnetic means for operating the signal, means for advancing the controller, means for restoring the controller, electromagnetically-operated means for actuating each of said advancing and restoring means energized in response to cars entering and leaving the block respectively, and means whereby the controller will be operated in response to each car in a predetermined order when cars enter and leave the block simultaneously.

11. In a signaling system, the combination of opposite signals at each end of a block, a step by step controller at each end of the block for controlling said signals, means for advancing and restoring the controllers, electromagnetic means for actuating 125

- each of said advancing and restoring means, energized by cars entering and leaving the block respectively, means for preventing the operation of one controller when the signals 5 have been set by the other, and means whereby said last controller will be operated in response to each car in a predetermined order when cars enter and leave the block simultaneously.
- 10 12. In a signaling system, a signal and a controller therefor, electromagnetically-actuated means for advancing and restoring the controller, controlling circuits for energizing the same, and means for energizing 15 one of said circuits in response to a passing car for a longer period than the other is energized.
13. In a signaling system, the combination of a signal, a step by step controller 20 therefor, means for advancing the controller, means for restoring the controller, electromagnets for operating each of said means, means for rendering one of the controller-operating means inoperative to move the 25 controller when the other means is operated, and means for rendering said first operating means operative after the controller completes its movement.
14. In a signaling system, the combination 30 of a signal, a signal controller therefor, means for advancing the controller, means normally disconnected from the controller for restoring the same, and means for preventing the actuation of the controller by 35 one of said means when the other means is operated, but permitting the actuation of said controller by the restrained means after the controller has been operated.
15. In a signaling system, the combination 40 of a signal, a controller therefor, means for advancing the controller, means for restoring the controller, means including an electromagnet for controlling and actuating each of said means, means for locking 45 one of said controller-actuating means against operation when the other is operated, and means for removing each of said controller-actuating means from the control of its magnet immediately upon the completion 50 of its stroke, substantially as described.
16. In a signaling system, the combination 55 of a step by step controller at the entering end of a block, means for advancing and restoring the controller, a movable signal at one end of the block having means including a circuit for operating the same, a distinguishing signal at the other end of the block, a circuit extending along the block for controlling the signals, a switch operated 60 by the controller for governing both signals, and means for operating one of said signals while the other is set.
17. In a signaling system, the combination 65 of a signal at the entering end of a block, a distinguishing signal at the remote end, a local circuit for said last signal, circuits extending along the block for controlling the signals, an electromagnetically - operated step by step signal controller at the entering end of the block, a switch operated by said controller in response to the first car entering and the last car leaving the block for setting and restoring the signals, said switch being independent of intermediate cars, and means for affecting the near signal while 70 the other is set.
18. In a signaling system, the combination of a danger signal having a normally closed circuit, a safety signal having a normally open circuit, means controlled 80 through said safety signal circuit for opening the danger signal circuit, means for affecting the safety signal when the danger signal circuit is opened, and means for opening and closing said safety signal circuit 85 while the danger signal circuit is open.
19. In a signaling system, the combination of a signal to be displayed at each end of a block, a block circuit through which the setting and clearing of each of said signals 90 is controlled, means for automatically displaying both of said signals when the first car enters the block, and means for automatically and momentarily clearing one of said signals when a subsequent car enters the 95 block.
20. In a signaling system, the combination of a signal to be displayed at each end of a block, a conductor by the energization and deenergization of which said signals 100 are controlled, means for automatically displaying both of said signals when the first car enters the block, and means operated in response to a subsequent car for automatically clearing and resetting one of said 105 signals while the other is displayed.
21. In a signaling system, a signal, a controller therefor, a pawl for advancing the controller, a pawl for restoring the controller, means for operating the pawls, and 110 means for effecting the restoration of one of the pawls immediately on the completion of its stroke and before the restoration of its operating means.
22. In a signaling system, the combination 115 of a signal, a controller therefor, means for advancing the controller, means for restoring the controller, means including electromagnets for controlling and actuating said means, and means for removing one of 120 said controller-operating means from the control of its magnet immediately upon the completion of its stroke.
23. In a signaling system, the combination 125 of a signal, a controller therefor, means for advancing the controller, means for restoring the controller, means including electromagnets for controlling and operating said means, said magnets capable of being simultaneously energized, and means for re- 130

moving each of said controller-operating means from the control of its magnet immediately upon the completion of its stroke.

24. In a signaling system, the combination of a signal, a step by step controller therefor, a pawl for advancing the controller, a pawl for restoring the controller, means including electromagnets for operating said pawls, and means for restoring each 10 of the pawls on the completion of its stroke, and independently of the condition of its operating magnet.

25. In a signaling system, a signal, a step by step controller therefor, pawls for advancing and restoring the controller, electromagnetically-controlled means for operating the pawls, and means for immediately disengaging each of said pawls from its operating means after it has operated 20 the controller and prior to the release of said operating means by its magnet.

26. In a signaling system, the combination of an electromagnetically-operated signal, step by step signal controllers having 25 electromagnetically - controlled restoring and advancing means, circuits for said electromagnets, a switch for preventing the improper operation of the restoring means, a signal circuit extending along the block, and 30 a relay in the circuit for setting the signal and opening the circuit to the advancing means at that end, substantially as described.

27. In a signaling system, the combination 35 of a signal at the entering end of a block, an opposite signal at the remote end of the block, a local circuit for said last signal, circuits extending along the block for controlling both signals, an electromagnetically-operated step by step signal controller at 40 the entering end of the block, a switch operated by said controller in response to the first and last car entering and leaving the block respectively for setting and clearing 45 both signals, said switch being independent of intermediate cars, and means for preventing the clearing of either of said signals in response to a car in entering at the remote end.

50 28. In a block signaling system, a normally deenergized signaling circuit extending along the block, electromagnetic signal-controlling means at one end operated through said circuit from the other end to 55 set a signal at its end, and a signal at the first end set through said circuit in response to the setting of the first signal without demagnetizing said controlling means.

29. In a block signaling system, a signal, 60 a single wire signal circuit extending along the block and normally connected to the same side of a source of power at each end, switch mechanism for energizing the circuit controlled by the first and last car of a possible series entering the block and independ-

70 ent of intermediate cars, signal-controlling means at one end energized through said circuit from the other end to set said signal at its end, and a signal at the other end set through said circuit upon the setting of the first signal without deenergizing said controlling means.

75 30. In a block signaling system, a signal circuit extending along the block, switches in said circuit, a signal at each end of the circuit set by one of said switches in response to the first of a possible series of cars entering the block, and another of said switches momentarily clearing one of said signals without altering the other in response to 80 each succeeding car, and means operated in response to the last car leaving the block for restoring both of said signals.

85 31. In a signaling apparatus, a signal and signal controller, electromagnetic means for advancing and restoring the controller, controlling circuits for the same, switches actuated in response to cars entering and leaving the block for controlling the circuits, and means operatively related with said 90 switches for delaying the deenergization of one of said circuits for a longer time than the other.

95 32. In a signaling apparatus, a step by step controller, electromagnetically-actuated means for advancing the controller, electromagnetically-actuated means for restoring the controller, means capable of simultaneously energizing said actuating means, and means operated to lock one of said electromagnetically-actuated means against movement until the controller has been actuated.

100 33. In a signaling apparatus, the combination of a step by step signal controller, means comprising electromagnets for advancing and restoring said controller, circuits for said magnets, means for controlling said circuits, and means actuated when one of said circuits is energized for locking one 105 of said controller-operating means against movement until the energized magnet has operated the controller.

110 34. In a block signaling apparatus, the combination of a step by step signal controller, electro-magnets for advancing and restoring the same, circuits for said magnets, switches in said circuits for energizing the same operated in response to cars entering and leaving the block, means for holding one of said switches closed for a shorter time 115 than the other, and means operated when one of said circuits is energized for rendering the magnet in the other circuit inoperative to move the controller until the energized magnet has operated the controller.

120 35. In a block signaling system, the combination of a normally-deenergized signal circuit extending along the block, signals at each end set through said circuit, electromagnetically-actuated step by step signal 125

controllers coöperatively related therewith, means for setting said signals in response to the first car entering the block, and means for affecting one of the said signals in response to each succeeding car for substantially the period during which said actuating means is energized.

36. In a block signaling system, a signal, a signal circuit therefor extending along the block and normally connected to a source of power at each end, contacts at each end for energizing said circuit, signal-setting means at one end controlled through said circuit for setting said signal at that end, means controlled by the setting of said signal for varying the current in the circuit, and a signal at the other end set in response to said current variation.

37. In a block signaling system, a signal, a signal circuit therefor extending along the block and normally connected to the same side of the source of power at each end, a switch in said circuit at each end for energizing the same, signal-setting means at one end controlled through the circuit from the other end for setting said signal, current-reducing means at that end controlled by the setting of the signal for varying the circuit energy, and a signal at the other end set through said line in response to said variation.

38. In a block signaling system, a signal circuit extending along the block, signal-setting means at one end controlled through said circuit to set a signal at that end, said signal, a signal at the other end set through said circuit in response to the setting of the first signal, and means for operating said second signal on the entrance of each car of a possible series into the block.

39. In a block signaling system, a signal circuit extending along the block, signal-setting means at one end controlled through said circuit by the first car of a possible series entering the block for setting a signal at that end, said signal, a signal at the other end set through said circuit in response to the setting of the first signal, and means for operating only said second signal by each succeeding car.

40. In a block signaling system, a signal circuit extending along the block, signal-controlling means including step by step mechanism associated therewith, a signal at one end of the block set through said circuit by the controller in response to the first car of a possible series entering the block, a signal at the other end of the block set through said circuit in response to the setting of the first signal, a switch controlled by each succeeding car of the series entering the block for operating said second signal only, and means for restoring both signals in response to the last car leaving the block.

41. In a block signaling system, a signal circuit extending along the block, switches in said circuit, a signal at each end of the circuit set by one of said switches in response to the first of a possible series of cars entering the block, one of said signals set in response to the other, another of said switches momentarily altering one of said signals in response to each succeeding car, and means operated in response to the last car leaving the block for restoring both signals.

42. In a block signaling system, the combination of a normally closed signal circuit at the far end of the block with reference to an incoming car, a normally open circuit at the near end, a circuit extending along the block, means at the far end of the block controlled through said block circuit for opening the normally closed circuit at said far end, contacts at said far end of the block circuit operated by the opening of said normally closed circuit to control said block circuit, and means at the near end of the block controlled through said block circuit upon the operation of said contacts for closing the normally open circuit at the near end.

43. In a block signaling system, the combination of a danger signal at the exit end of the block, a distinguishing signal at the entrance end of the block, a local circuit for each signal, electromagnetic means for controlling each circuit, a circuit extending along the block by the energization and de-energization of which said electromagnetic means are operated to set and clear said signals, a step-by-step signal controller at the entering end of the block and a step-by-step controller at the exit end of the block, means operated by said controllers for energizing and deenergizing said block circuit to control the signals, electromagnetically operated means for advancing the controller at the exit end of the block and an operating circuit for said means, and contacts in said operating circuit controlled through said block circuit for preventing the operation of said controller when the danger signal at the exit end of the block is set.

44. In a signaling system, the combination of a plurality of signals at each end of a block, a local circuit for each of said signals, a controlling relay for each of said circuits, a signal circuit extending along the block and having branches at each end for energizing the relays, and at each end of the block electromagnetically-operated means for opening and closing the branches, said means opening one branch when it closes the other.

45. In a block signaling system, the combination of a danger signal and a distinguishing signal at each end of the block, a local circuit for each signal, electromag-

netically operated means controlling each local circuit, a line wire extending along the block and having a ground and a positive branch at each end, one branch for each of said electromagnetically operated means, a signal controller with means operated thereby, at each end of the block controlling the branch circuits at its end to open one and close the other to establish a circuit through 5 a positive branch at one end of the line wire and a ground branch at the other end, means for advancing the controllers including an electromagnet and an operating circuit for each, contacts in each of said operating circuits respectively controlled responsive to current in the branch circuit controlling the danger signal at its end, for preventing a car entering at the exit end of the block from affecting the signals previously set by a 10 car at the entering end.

46. In a block signaling system, the combination of a plurality of signals, a controller therefor, a local circuit for each of said signals, electro-magnetically operated 15 means controlling each of said circuits, a signaling circuit extending along the block and having a branch for each of said electro-magnetically operated means, and means operated by the controller controlling said branch circuits, and to open one when it 20 closes the other.

47. In a block signaling system, the combination of a plurality of signals at one end of a block, a local circuit for each of said 25 signals having contacts therein, a relay for controlling the contacts in each of said circuits, a signal controller, a signal circuit extending along the block and having a branch for each of said relays, contacts in 30 each of said branches, and means operated by the controller for closing the contacts in one of said branches and opening the contacts in the other branch.

48. In a block signaling system, the combination of distinguishing signals at one 35 end of the block, local circuits for each of said signals, contacts in each of said circuits, a relay for controlling each of said contacts, an electro-magnetically operated signal controller, a signal circuit extending along the 40 block and having a branch for each of said relays, and means operated by the controller for simultaneously opening one of said branch circuits and closing the other.

49. In a block signaling system, the combination of a pair of distinguishing signals at each end of the block, a local circuit for each signal, a relay controlling each of said 45 circuits, a signal controller at each end of the block controlling said relays, electromagnetic means operating the controllers in response to cars entering and leaving the block, a signal circuit extending along the block and having a normally open and a normally 50 closed branch at each end including said

relays, and means operated by one of the controllers in response to a car entering the block to close a circuit through the normally open branch at its end and the normally closed branch at the other end and simultaneously to open the normally closed branch 70 at its end.

50. In a block signaling system, the combination of a step by step controller, electro-magnetic means operating selectively to advance and restore the same, circuits for said means, a contact near one end of the block operatively related to one of said circuits and engaged by a passing car for energizing said circuit, and means including a contact 75 near the other end of the block operatively related to the other circuit for closing the same, one of said contacts being closed for a longer period than the other.

51. In a signaling system, the combination 80 of a step-by-step controller, electromagnetic means selectively advancing and restoring the same, circuits for said means, a contact near one end of the block engaged by a passing car for energizing one of said circuits, and contacts near the other end for energizing the other circuit, the first contact being elongated so that when it is engaged by a car simultaneously with the closing of the contacts at the opposite end of the block 85 by another car, the first circuit will be energized for a longer time than said second circuit.

52. In a signaling system, the combination 90 of a signal, a step by step controller therefor, a plurality of electromagnets for governing the operation of the same, an insulated contact piece placed beside the power conductor to be engaged by the collector of a car, an electromagnet connected between said 95 contact piece and a source of current, said magnet controlling the energization of one of the controller governing magnets and operatively energized by completing the circuit from the contact through the car, and 100 separate means for energizing the other governing magnet.

53. In a block signaling system, the combination of a signal, a step by step controller therefor, electro-magnetically controlled 105 means for advancing and restoring the controller, a circuit for governing the operation of the restoring means, a switch for controlling said circuit, electromagnetic means operating said switch, an elongated contact 110 engaged by a passing car, and a connection from a source of current to said contact including the electromagnetic switch operating means, whereby the controller may be operated by the closing of a switch on the car.

54. In a signaling system, the combination 115 of a signal, a step by step controller therefor, means for advancing and restoring the controller, electric circuits for governing the 120 operation of said means, a switch mechani- 125

5 eally operated by a passing car for energizing one of said circuits, a switch for closing the other circuit, a solenoid for operating said switch, an elongated contact engaged by a passing car, and a circuit including said contact and solenoid.

55. In a signaling system, the combination of a signal at one end of the block, a step-by-step controller therefor, electromagnetically controlled means for advancing and restoring the controller, electric circuits for governing the operation of said means, a switch at one end of the block operatively related to one of said circuits and mechanically closed in response to a passing car for energizing one of said controlling means, a switch at the other end of the block operatively related to the other circuit, electromagnetic means operating said switch, a circuit including said means energized by a passing car, and means for locking one of the controller operating means against movement until the controller has been actuated by the other operating means.

25 56. In a signaling system, the combination of a signal, a step by step controller therefor, pivotal means for moving the controller to set the signal, pivotal means for moving the controller to clear the signal, electro-magnets for operating each of said means, and means for preventing the actuation of the controller by one of said pivotal means when the other is operated, and means releasing the restrained means as soon as the controller has been actuated, and independently of the deenergization of its actuating magnet.

57. In a signaling system, the combination of a signal, a controller therefor, means for advancing the controller, means for restoring the controller, electro-magnets for operating each of said means, means for restraining one of the controller operating means when the other means is operated, and means for releasing said restrained means upon the completion of the controller movement and prior to the deenergization of its actuating magnet.

58. In a signaling system, the combination of a signal, a step by step controller therefor, means including an electro-magnet for advancing the controller, means including an electro-magnet for restoring the controller, means for locking one of the electromagnetically operating means against movement when the other means is operated, and means rendered operative immediately upon the completion of the controller movement for unlocking said operating means.

60 59. In a signaling system, the combination of a signal, a step by step controller therefor, electro-magnetically operated means for advancing the controller, electro-magnetically operated means for restoring the controller, a latch operated by one of

said means to lock the other against operating the controller, and means for effecting the release of said latch to unlock said means immediately that the first operating means completes its forward movement.

60. In a signaling system, the combination of a signal, a step by step controller therefor, electro-magnetically operated means for advancing the controller, electro-magnetically operated means for restoring the controller, a latch operated by one of said means to lock the other against operation, and means operated at the completion of the controller movement for disengaging said latch from its operating means to unlock said other operating means.

61. In a signaling system, the combination of a signal, a step by step controller therefor, pawls for advancing and restoring the controller, means including electromagnets for actuating said pawls, means engaged by a part of one of said actuating means for locking one of the pawls against movement when the other is operated, and means moved with said last actuating means to immediately unlock said first pawl when said actuating means has completed its stroke.

62. In a block signaling system, the combination of a danger signal at one end of the block, a safety signal at the other end of the block, a local circuit for each of said signals, means for opening the danger signal circuit and closing the safety signal circuit when a car enters the block, a switch, and electromagnetically operated means with an operating circuit therefor for operating said switch in response to cars entering the block to open and close the safety signal circuit in response to each car entering the block while the danger signal circuit is open.

63. In a block signaling system, the combination of a signal at the remote end of the block, a distinguishing signal at the near end of the block, a local circuit for each of said signals, a step by step controller for setting both signals when a car enters the block, and a switch operatively related to the controller to be actuated when the controller is operated in response to subsequent cars entering the block for momentarily changing said near signal while the other signal is set.

64. In a block signaling system, the combination of a signal at the remote end of the block, a distinguishing signal at the near end of the block, a local circuit for each signal, electro-magnetically operated means for controlling each circuit, a circuit extending along the block for energizing each of the electro-magnetically operated means, means including a step by step controller for closing said last circuit to actuate said magnetically operating means to set the signals

when a car enters the block, and a switch operatively related to the controller to be actuated when the controller is operated in response to subsequent cars entering the block for clearing and resetting one of said signals while the other is set.

In testimony whereof I affix my signature,

in presence of two witnesses, this 24th day of December, 1907.

SAMUEL M. WARD, Jr.
